UNITED STATES PATENT OFFICE

GEORGE J. RILEY, OF ELKINS PARK, PENNSYLVANIA

BOUQUET HOLDER

Application filed March 14, 1931. Serial No. 522,558.

My invention relates to bouquet holders which are adapted for use in the holding or supporting of a bouquet and the attaching of the same to the corsage portion of a woman's dress or gown.

The general object of the invention is to provide a holder of simplified but novel construction having means which enables the fastening of a bouquet thereto.

10 The invention consists in the construction and arrangement of parts therein as herein-after described in detail, particularly pointed out in the claims and as illustrated in the drawing wherein I have illustrated a mechanical embodiment of the holder in the form which at present is preferred by me.

In order that the invention may be readily understood and its practical advantages fully appreciated reference should be had to the accompanying drawing forming a part of this specification and wherein

Fig. 1 is a view in perspective of a holder embodying the invention and also showing in dotted lines a portion of a ribbon or other suitable means by which the bouquet may be fastened to the holder;

Fig. 2 is a view in longitudinal section of the holder taken on the line 2—2 of Fig. 1 and showing also the stem or handle of a bouquet in section and the fastening means for securing the bouquet to the holder in elevation; and

Fig. 3 is a view in transverse section of the holder and showing in dash lines the stem or handle portion of the bouquet in place thereon.

The construction embodying my invention is shown as consisting of wire bent into a form similar to that which is embodied in certain well known paper clips but it may consist of other material than wire provided that it shall embody means the equivalent of that shown in the drawing to enable the fastening of a bouquet in place thereon.

45 In the drawing I have shown a clip consisting of wire bent so as to form bottom and top gripping portions 1 and 2, which portions are held in gripping relation to each other by the spring action of the metal of the clip.

50 The front or engaging end of the bottom

gripping member 1 of the clip projects a distance beyond the front end of the top gripping member 2, as indicated at 3, to facilitate the engagement of the clip with a portion of the corsage of a woman's dress or gown. Preferably also the projecting portion 3 is tapered in some such manner as is shown in Fig. 1 of the drawing. The opposite or rear end of the clip comprises two base end bars 4 and 5, the former being located 55 outside of the latter. The side 6 of the top gripping member 2 is connected at one end to an end of the end bar 4 and extends forward in overlying relation to the side 7 of the gripping member 1. The opposite sides of 60 the gripping members 1 and 2 are arranged in reverse relation; that is, the side 7' of the bottom gripping member 1 is located underneath the adjoining side 8 of the top gripping member 2. The overlying relation of the 65 opposite sides of the gripping members 1 and 2 as described operates to hold the said gripping members in gripping relation to each other.

In order to provide means for fastening or securing a bouquet to the holder I have bent inwardly or indented the central portion of the end bar 5, as shown at 10, and of the front bar 11, as shown at 12, thereby providing projections 13 and 14 at the opposite ends 70 of the said bars respectively. The inwardly bent or indented portion 10 of the bar 5 by reason of the presence of the bar 4 provides an opening 15 of rectangular shape, as shown in Fig. 1, through which a ribbon or other 75 fastening means 16 may be extended as shown. Such ribbon or other fastening means also is passed through the opening provided between the end portion 3 of the bottom gripping member and the front end 80 bar 11 of the top gripping member. The indented or inwardly bent portions 10 and 12 of the front and rear bars 5 and 11 provide seats within which the ribbon or other fastening means is located. The projections 13 and 14 prevent lateral displacement of the ribbon. In other words, the said projections 85 retain the ribbon or other fastening means in place upon the holder. In the use of the device the stem or handle 17 of the bouquet 90

100

is placed in position upon and extending crosswise of the top gripping member 2 of the clip after which the ribbon or other fastening means 16 is drawn about the said stem 5 or handle and about the indented portions 10 and 12 of the bars 5 and 11 and tied against the stem 17, as indicated at 18, with sufficient tightness to hold the bouquet in place upon the holder. This having been done the holder 10 is then clipped to the garment, such as a corsage, by inserting a portion thereof into position between the gripping members 1 and 2 in the same manner as sheets of paper are fastened between the gripping members 15 of one type of well known paper clips.

It is not essential that the bouquet be fastened to the clip before the latter is fastened to the garment but if desired the clip may be fastened to the garment, the bouquet placed 20 in position thereon and then fastened thereto by tying the ribbon or other fastening means 16.

Having thus described my invention, what I claim and desire to secure by Letter Patent is:

1. A bouquet holder comprising a clip having co-operating gripping members and provided with projections at the opposite edges thereof in adjoining relation to its opposite 30 ends for retaining a fastening means in place thereon.

2. A bouquet holder comprising gripping elements held in yielding gripping relation to each other and having cross bars at the 35 opposite ends thereof the central portions of which are indented to provide seats for receiving fastening means for securing a bouquet upon the holder.

3. A bouquet holder consisting of a spring 40 clip having gripping elements arranged in gripping relation to each other, and bars at the opposite ends of said clip having their central portions bent inwardly toward each other, the opposite ends of said bars terminating in outwardly extending projections 45 to form shoulders which are adapted to retain upon the holder a fastening means employed to secure a bouquet thereon.

4. A bouquet holder consisting of a spring 50 clip formed of wire, the said wire being bent to form bottom and top gripping elements arranged in gripping relation to each other, and front and rear end bars which are arranged in angular relation to each other, one 55 bar being located rearwardly of and in adjoining relation to the other, one end of the said rear bar being located on one side of a side bar of the bottom gripping element and the other end thereof being located on one 60 side of a side of the top gripping element, the central portion of the rear end bar being indented and the central portion of the front end bar of the top gripping member also being indented, the indentations of the said bars 65 forming seats for the reception of a fasten-

ing means for securing a bouquet to the said holder.

5. A bouquet holder consisting of a spring wire clip having gripping elements arranged in gripping relation to each other and having at its ends end bars in spaced relation to each other over which a fastening means may be passed, and the said clip having at its opposite ends in adjoining relation to the opposite edges thereof means for retaining the said fastening means in place thereon.

In testimony that I claim the foregoing as my invention I have hereunto signed my name this 12th-day of March, A. D. 1931.
